UNITED STATES PATENT OFFICE.

EDWARDO H. GUERRERO, OF SAN ANTONIO, TEXAS.

COMBINED SPANNER AND WRENCH.

1,405,207.

Specification of Letters Patent. Patented Jan. 31, 1922.

Application filed July 7, 1921. Serial No. 483,019.

To all whom it may concern:

Be it known that I, EDWARDO H. GUERRERO, a citizen of the United States, residing at San Antonio, in the county of Bexar and 5 State of Texas, have invented certain new and useful Improvements in Combined Spanners and Wrenches; and I do declare the following to be a full, clear, and exact 10 description of the invention, such as will enable others skilled in the art to which it appertains to make and use the same.

This invention relates broadly to improvements in tools and has particular reference to a device of this class which functions as 15 a spanner for engaging the lugs on hose couplings for rotating said couplings and also acts as a wrench, this part being designed more especially for turning the usual nut on top of a fire hydrant to open the 20 valve.

The principal object of the invention, as above indicated, is to provide a single tool which serves the purpose of two tools which are ordinarily required for the purposes 25 mentioned.

Another object of the invention is to generally improve upon devices of this class by the provision of one of extreme simplicity and durability which embodies pawl and 30 ratchet mechanism, thus enabling short movements of the handle to be employed for rotating the nut on the hydrant instead of rotating the handle through a complete revolution as is ordinarily done with the common 35 type of wrenches now employed for this purpose.

Other objects and advantages of the invention will be apparent during the course of the following description.

40 In the accompanying drawings forming a part of this specification and in which like numerals are employed to designate like parts throughout the same:

Figure 1 is a top plan view, with parts 45 shown in section, of a tool constructed in accordance with this invention.

Figures 2 and 3 are sectional views taken substantially on the planes of the lines 2-2 and 3-3 respectively of Fig. 1.

50 In carrying out the invention, I employ a handle 1 which is equipped at its outer end with substantially circular ring-like enlargements 2 constituting a head, the latter being formed on one side with a lateral enlargement 3 arranged adjacent the point of con-

nection on the head and handle. It is to be noted that at least one of the vertical edges of the handle and enlargement 3 is flat, and this edge is gradually curved to provide a portion of a circle, this portion of the tool 60 constituting an arcuate abutment to rest on a portion of the hose coupling C. It is to be noted that the abutment 4 adjacent its terminal is formed with a notch 5, which constitutes what may be termed a spanner, 65 the same being adapted as is obvious, to receive one of the lugs L therein for the purpose of imparting rotation to the coupling C. From the foregoing it will be seen that the portion of the tool which serves as 70 a spanner for turning hose couplings has been described. The wrench designed for turning the nut on fire hydrants will now be described.

To this end, it will be seen that a ratchet 75 6 is arranged for rotation within the ring or head 2 and this is equipped with a central non-circular hole 7 designed for gripping a flat faced object such as a nut. Face-plates 8 are secured on opposite sides of 80 the head and are wider than the latter and extend inwardly beyond the inner edge thereof and cover portion of the ratchet 6 so as to serve as a sole retaining means for this part of the tool. The head adjacent 85 the enlargement 3 is formed with a recess 9 to accommodate a spring-pressed dog 10 pivoted to the head as indicated at 11. The spring for actuating the dog is designated by the numeral 12 and is arranged in a trans- 90 verse hole 13 which extends through the enlargement 3. At one end, the spring surrounds a suitable pin 14 on one side of the dog and at its opposite end it bears against a removable plate 15 which serves to close 95 the outer end of this opening 13.

The abutment 4 of the tool is shaped to conform to the periphery of the coupling C such as found on the fire-engine hose, thus permitting the spanner notch 5 to be easily 100 and conveniently engaged with one of the lugs L on this coupling. If it is desired to use the device for turning the supply of water of a fire hydrant off or on, this can be done by simply engaging the non-circular 105 opening of the ratchet with the usual nut on top of the hydrant and moving the handle back and forth for rotating this ratchet as is usual with devices of this type.

By carefully considering the description 110

in connection with the drawings, persons familiar with devices of this class will doubtless be able to obtain a clear understanding of the invention. Therefore, a more lengthy and detailed description is deemed unnecessary.

Since probably the best results may be obtained with the construction and arrangement herein shown and described, this is taken as the preferred embodiment of the invention. However, I wish it to be understood that minor changes coming within the scope of the subjoined claims may be resorted to if desired.

15 I claim:

1. A combined ratchet wrench and spanner wrench comprising a handle having a

ratchet receiving head at its front end, said head being provided with an integral dog-carrying projection having means at its exterior co-operable with said handle in forming a spanner wrench.

2. A combined ratchet wrench and spanner wrench comprising a handle having a ratchet receiving head at its front end, said head being provided with an integral lateral projection internally recessed to accommodate a ratchet operating dog and externally notched to co-act with the handle in forming a spanner wrench.

30 In testimony whereof I have hereunto set my hand.

EDWARDO H. GUERRERO.
